CLAIM

I claim the ornamental design for a T-shirt with front opening, as shown and described.

DESCRIPTION

FIG. 1 is an exploded perspective view of a T-shirt with front opening, showing my new design;

FIG. 2 is a perspective view thereof;

FIG. 3 is a front elevational view thereof;

FIG. 4 is a rear elevational view thereof;

FIG. 5 is a left-side elevational view thereof; the undisclosed right-side elevational view being a mirror image thereof;

FIG. 6 is a top plan view thereof; and,

FIG. 7 is a bottom plan view thereof.

The broken lines in the figures represent stitching, and are part of the claimed design.
